UNITED STATES PATENT OFFICE.

EDWARD HETT, OF NEW YORK, N. Y.

SYSTEM FOR HANDLING PRINTING-CYLINDERS.

SPECIFICATION forming part of Letters Patent No. 637,584, dated November 21, 1899.

Application filed January 3, 1899. Serial No. 700,925. (No model.)

To all whom it may concern:

Be it known that I, EDWARD HETT, a citizen of the United States, and a resident of New York, (New Dorp,) in the county of Richmond, 5 State of New York, have invented a certain new and Improved System for Handling Printing-Cylinders, of which the following is a specification.

My invention relates to printing and transfer presses, and particularly to devices for handling printing-cylinders or printing-tubes in connection with such presses.

It has for its object the rapid, ready, and convenient handling of printing cylinders or tubes or supports therefor, particularly in connection with their introduction into and removal from operative position in the press.

It consists of the novel devices herein shown and described.

20 The preferred form of my invention, which is shown in the drawings herein, is shown in connection with a multicolor-press, although obviously it can be used with any kind of printing or transfer press in which printing cylinders, tubes, or supports therefor are used.

In the accompanying drawings, which form a part hereof and which show the preferred form of my improved device and in which 30 the same reference characters in the different figures refer to corresponding parts, Figure 1 is a view showing in a diagrammatical manner the electric circuits used in connection with and for the purpose of controlling the 35 movements of the movable carriage and its operative parts. Fig. 2 is a plan of the movable carriage. Fig. 3 is a side view of the same. Fig. 4 is a side view of a multicolor-press, showing my improved devices applied 40 thereto; and Fig. 5 is a detail of part of my improved device. Fig. 6 is a diagram illustrating the circuit through the fields of the motor and certain modifications in the circuits.

45 Referring to the specific forms of apparatus shown in the drawings, 1 indicates the frame of a multicolor-printing press, of which 2 is the impression-drum and 3 are the printing-cylinders in position in the press.

50 4 are brackets pendent from the ceiling or other suitable support. These brackets are arranged on both sides of the press and

support or carry rails 5, which are provided at one side with rack-teeth 6, as shown in Fig. 4. A movable carriage 7 is arranged to 55 run upon rails 5 and is provided with a number of wheels 8, which bear upon the rails both upon the upper and the under side. One set of these wheels is provided with a wheel having teeth to fit into the racks 6. 60 This set of wheels I have designated as 8^a. By means of these wheels the carriage is adapted to move along the rails 5 and rack 6, so that it can be brought into any position.

The carriage is provided with suitable hoist- 65 ing-arms 9, which are adapted to be lowered and raised and are adapted to seize and to raise or lower printing-cylinders or printing-tubes and their supports. Any suitable form of hoisting-arms and any suitable mechanism 70 for raising and lowering them may be employed. As these form no part of my present invention, I will not further describe them herein, except to say that the hoisting-arms shown in the drawings are made substantially 75 like the hoisting-arms shown and described in an application executed and filed by me simultaneously herewith and known as Serial No. 700,924 for an improvement in tube-handling devices. Fig. 3 represents the hoisting- 80 arms as carrying a printing-cylinder 10. In practice the movable carriage is moved forward and backward along the rails to the proper position and the hoisting-arms are lowered to introduce a printing-cylinder in proper 85 position in the press or to withdraw it from such position.

Movable carriage 7 is moved along the rails and motion is also imparted to the hoisting- 90 arms by means of an electric motor 11, mounted upon the framework of the carriage. This motor may be of any suitable construction. It is driven in the manner presently to be described. Upon the shaft 12 of the motor is mounted a gear-wheel 13. (See Figs. 1 and 2.) This gear-wheel meshes with large gear-wheel 14, mounted upon a sleeve 15, which runs loosely upon shaft 16. Also mounted upon the same sleeve 15 are gear-wheels 17 and one part 18^a of clutch 18. The other 100 part 18^b of the clutch 18 is fast upon shaft 16. Clutch 18 is an electric clutch and can be made of any suitable construction. Upon one end of shaft 16 is bevel gear-wheel 19,

meshing with bevel gear-wheel 20 on shaft 21; the latter shaft carrying worm 22 at its other end, which meshes with worm-wheel 23 on shaft 24. At the end of the shaft 24 is toothed wheel 8^a, which meshes with teeth of rack 6. When the motor 11 is running, motion is imparted to the movable carriage by energizing electric clutch 18, thus causing shaft 16 to rotate with gear-wheel 14 and through the bevel-gears, the worm, and worm-wheel driving toothed wheel 8^a and moving the carriage along the rails. Clutch 18 is energized and de-energized in the manner presently to be described. Motion is imparted to the hoisting-arms by means of the following-described mechanism: Gear-wheel 17 meshes with gear-wheel 25, mounted on short shaft 26, turning in bearings 27. Gear-wheel 25 also meshes with gear-wheel 28, loosely mounted on shaft 29. The same sleeve 30 which carries gear-wheel 28 also carries part 31^a of clutch 31. The other part 31^b of the clutch is fast upon shaft 29. Shaft 29 carries at each end bevel gear-wheels 32. Each of these bevel gear-wheels meshes with a bevel gear-wheel 33, which is on a screw 34, which drives hoisting-arm 35. The details of the mechanism by which this is accomplished form no part of my present invention and are therefore not described in further detail.

By energizing clutch 31 when the motor is running motion is imparted to the hoisting-arms. Motion of the carriage one way or the other and motion of the hoisting-arms up or down are determined by means of a reversing-switch, which determines the rotation of the motor one way or the other, as desired, in the manner presently to be described.

I will now proceed to describe the electric circuits by means of which the motor is driven in one direction or the other and how the different clutches are energized to drive the carriage one way or the other on the rails and how the hoisting-arms are operated.

I place the motor and each of the electric clutches each in an electric circuit containing a circuit-controller which is under the control of the operator. Preferably I place the circuit-controller under the control of the operator by means of a separate and distinct circuit, which, for convenience, I herein designate as an "operating-circuit." This operating-circuit is controlled by the operator touching, preferably, a push-button. Each circuit-controller is opened, preferably, by the operator closing a releasing-circuit containing a magnet, which withdraws a catch which held the circuit-controller in closed position. The operator closes the releasing-circuit preferably by touching another push-button. The electric motor is thus energized or de-energized, and each electric clutch is energized or de-energized at will by merely touching the appropriate push-button, and the direction of rotation of the motor is determined by an ordinary reversing-switch.

I will now proceed to describe my preferred devices for accomplishing the above purposes.

37 is a switch, of any ordinary construction; for connecting or disconnecting with any suitable source of electrical supply. 70

38 39 are wires which connect the switch with suitable metallic strips 40 41, suitably secured to rails 5 and insulated therefrom in any appropriate manner. Strip 41 is connected by wire 42 with one of the binding-posts of reversing-switch 43 and strip 40 is connected by wire 44 with another binding-post of the same reversing-switch. This reversing-switch is of any ordinary construction and is 80 so arranged as to reverse the current by turning the switch.

The circuit through electric motor 11 is as follows: from the source of electrical supply, through switch 37, wire 38, strip 40 on one of 85 the rails 5, wire 44, reversing-switch 43, wire 45, contact-point 46, bridge 47 of circuit-controller 48, contact-point 49, wire 50, motor 11, wire 51, contact-point 52, bridge 53 of circuit-controller 48, contact-point 54, wire 55 to the 90 other side of the reversing-switch 43, wire 42, strip 41, wire 39, back to switch 37, to the other wire of the source of electrical supply. This circuit is normally broken at circuit-controller 48. This circuit-controller is placed 95 under the control of the operator. It is closed by him by pushing in push-button 56. This closes a circuit through magnet 57. For convenience this circuit and said magnet will hereinafter be spoken of as an "operating-circuit" and an "operating-magnet." This operating-circuit is normally broken at push-button 56. When the push-button is pressed in, the circuit is closed, magnet 57 is energized, and circuit-controller 48, which is the 105 armature-bar of magnet 57, is closed, thus closing the circuit through the motor. The operating-circuit through push-button 56 and magnet 57 is as follows: push-button 56, wire 58, magnet 57, wire 55 to one side or the other 110 of the reversing-switch, depending on how that said switch is set, and then through wire 42 or wire 44 to one side or the other of switch 37, also from push-button 56, through wire 59, wire 45, to the other side of the reversing-switch, and thence to the opposite side of switch 37. The pushing in of push-button 56 thus closes the operating-circuit through magnet 57 and closes circuit-controller 48. This 115 closes the circuit through the motor.

As the pressing upon button 56 would ordinarily be but momentary, I provide means for holding circuit-controller 48 in its closed position. This mechanism consists of a catch 60, which locks circuit-controller 48 in its 120 closed position, holding it in this position until the catch is removed, as hereinafter described. The motor is stopped by the operator pressing upon a push-button 61, which closes a circuit through magnet 62. For convenience this 125 circuit and magnet will be spoken of herein as the "releasing-circuit" and the "releas-

ing-magnet." The releasing-circuit consists, preferably, of the following: wire 63, running from one side of the push-button 61 and connecting with wire 59, thence through wire 59, 5 wire 45 to one side of the reversing-switch, from the other side of push-button 61, through wire 64, wire 65, releasing-magnet 62, wire 66, releasing-magnet 67, wire 68, releasing-magnet 69, wire 70, part of wire 51, contact-point 52, bridge 53, contact-point 54, wire 55, to the other side of the reversing-switch. By pressing upon push-button 61 the operator thus energizes releasing-magnets 62 67 69, and, among other things, withdraws catch 60 10 from operative connection with circuit-controller 48, permitting that circuit-controller to fall back into its normal open position. It will of course be understood that circuit-controller 48 is kept in its open position by springs 15 or other suitable devices for that purpose. The operator can thus at will, by pressing upon push-buttons 56 or 61 and by turning the reversing-switch 43 one way or the other, cause motor 11 to rotate in one direction or 20 the other or to cease from rotation.

Clutch 18 is energized and deenergized in the following manner: For the purpose of controlling this clutch I also employ a circuit containing a circuit-controller, preferably 25 normally open, which is under the control of the operator through an operating circuit and magnet, the latter being closed by pressing upon a push-button, being held closed by means of a catch, and the catch being released through a releasing circuit and magnet, which are respectively closed and energized by pressing upon another push-button, substantially in the manner described above for the circuits employed in connection with 30 the motor. These circuits are as follows: The circuit through clutch 18 passes through wire 71, contact-points, and one of the bridges of circuit-controller 72, wire 73, to wire 44, thence to one side of switch 37; also from 35 clutch 18 through wire 74, through contact-points and the other bridge of circuit-controller 72 and wire 75 to wire 42, and thence to the other side of switch 37. The operating-circuit is as follows: Push-button 76, 40 where the circuit is normally broken, wires 77 and 73 to wire 44, and thence to one side of the switch 37; also from push-button 76 to wire 78, to operating-magnet 79, wire 75, to wire 42, and thence to the other side of switch 45 37. By depressing push-button 76 the operator energizes magnet 79, closing circuit-controller 72. Catch 80 seizes and holds this circuit-controller in its closed position until released by releasing-magnet 69. The releasing-circuit through the magnet 69 is as follows: Push-button 81, wire 82, wire 65, magnet 62, wire 66, magnet 67, wire 68, magnet 69, wire 70, part of wire 51, contact-points and one of the bridges of circuit-controller 48, wire 55 to one side of reversing-switch 43; also from push-button 81 through wire 83, wire 84, wire 59, wire 45 to the other side of

reversing-switch 43. By pressing upon push-button 81 the operator thus energizes releasing-magnet 69, as well as releasing-magnets 67 and 62, and, among other things, withdraws catch 80 from operative connection with circuit-controller 72, permitting that circuit-controller to fall back into its normal open position, thus breaking circuit through 75 clutch 18 and deenergizing that clutch. The operator can thus at will, by pressing upon push-buttons 76 or 81, cause clutch 18 to be energized or deenergized, thus causing the carriage to be driven along the rails or to stand still. By means of reversing-switch 43 the direction of motion of the carriage one way or the other upon the rails can be controlled through the reversal of the direction of rotation of the motor. 85

Clutch 31 is energized and deenergized in the following manner: For the purpose of controlling this clutch I employ a similar circuit and circuit-controller and a similar operating circuit and magnet, and a similar catch and releasing circuit and magnet, and similar push-buttons. These circuits are as follows: The circuit through clutch 31 passes through wire 85, one set of contact-points and bridge of circuit-controller 86, wire 87, wire 44, strip 40, 90 wire 38 to one side of switch 37; also from clutch 31, through wire 88, the other set of contact-points and bridge of circuit-controller 86, wire 89, wire 42, strip 41, and wire 39 to the other side of switch 37. The operating-circuit is as follows: Push-button 90, where the circuit is normally broken, wires 91 and 87, wire 44, strip 40, wire 38, to one side of the switch 37; also from push-button 90, wire 92, operating-magnet 93, wire 89, wire 42, 95 strip 41, wire 39, to the other side of switch 37. By depressing push-button 90 the operator energizes operating-magnet 93, closing circuit-controller 86, and thus closing the circuit through clutch 31. Catch 94 seizes and holds circuit-controller 86 in its closed position until released by releasing-magnet 67 in the following manner: The releasing-circuit through this magnet is as follows: Push-button 95, wire 96, wire 65, magnet 62, wire 66, magnet 67, wire 68, magnet 69, wire 70, part of wire 51, contact-points, and one of the bridges of circuit-controller 48, which are of course always in their closed position when clutch 31 is energized, wire 55 to one side of reversing-switch 43; also from push-button 95, through wire 84, wire 59, wire 45, to the other side of reversing-switch 43. By pressing upon push-button 95 the operator thus energizes releasing-magnet 67 along with magnets 62 and 69 100 and withdraws catch 94 from operative connection with circuit-controller 86, thus permitting that circuit-controller to fall back into its normal open position, breaking the circuit through clutch 31 and deenergizing that clutch. It will of course be understood that circuit-controller 86, as well as circuit-controller 72, is kept in its open position by springs or other suitable devices for that pur- 105 110 115 120 125 130

pose. The operator can thus at will by pressing push-buttons 90 and 95 cause clutch 31 to be energized or deenergized, thus moving hoisting-arms 35 or causing them to stand still. The movement of the hoisting-arms upward or downward will depend upon the direction of rotation of the motor.

By my improved devices rotation in one direction or the other can be imparted to the motor and the carriage be driven in one direction or the other upon the rails, as desired, and be stopped at any desired point thereon, and the hoisting-arms can be lowered or raised at will.

15 The devices for bringing printing-cylinders or printing-tubes or supports therefor to the carriage and hoisting-arms or for taking them away from no part of my present invention, and no devices for that purpose are here shown or described. They may be brought to or removed from the carriage and hoisting-arms by hand or by any suitable means.

By means of my improved devices printing-cylinders or printing-tubes or supports therefor for presses can be rapidly, readily, and conveniently handled and can be introduced into and removed from operative position in the press rapidly and conveniently.

My improved devices are of peculiar value 30 in multicolor-presses, such as the one shown in the drawings, or in any presses in which there are a large number of printing-surfaces.

In order to insure the stoppage of the carriage with certainty at any predetermined point upon the rails, I provide automatic means for breaking the circuit through the motor and through clutch 18. My preferred devices for this purpose consist of the following: At each point where I desire the carriage to stop for the purpose of introducing printing cylinders or tubes or supports into the press or for removing them therefrom I place a switch which can be so arranged that when the carriage reaches that point upon the rails the releasing-circuit through the releasing-magnets will be closed, the catches for the circuit-controllers 48, 72, and 86 will be withdrawn, and the circuits through the motor and the clutches be broken. 35 97 97^a represent two of these switches for stopping the carriage while moving in one direction, one of them, 97^a, being shown in its open or non-operative position and the other, 97, in its closed or operative position. Each of these switches connects by a wire 98 with the strip upon one of the rails, as shown with strip 40. On the other side each switch is adapted to be connected with the wire 99, which leads 40 to a contact-point 100. A contact-point 101 on the carriage is adapted as the carriage moves along the rails to make contact with the different contact-points 100. If it is desired, for example, to stop the carriage at the 45 switch 97, that switch is turned into the operative position, (shown at 97 in Fig. 1.) When the carriage reaches this point upon the rails,

contact-points 101 and 100 make contact with each other, and this closes a circuit through the releasing-magnets. This circuit is as follows: The switch 37, wire 38, strip 40, wire 98, switch 97, wire 99, contact-points 100 101, wire 102, wire 65, releasing-magnet 62, wire 66, releasing-magnet 67, wire 68, releasing-magnet 69, wire 70, part of wire 51, one set 70 of contact-points and bridge of circuit-controller 48, wire 55, to one side of reversing-switch 43, wire 42, strip 41, wire 39, to the other side of switch 37. In this way the releasing-magnets are automatically energized 75 when the carriage reaches the desired stopping-point on the rails, the catches are withdrawn, and the circuit-controllers are opened to break the circuit through the electric motor and through the clutches, particularly 80 clutch 18, thus insuring the immediate and automatic stoppage of the carriage at the desired point.

In order to insure the stoppage of the upward movement of the hoisting-arms at the proper point, I arrange, preferably, a contact-point on one of the hoisting-arms, so arranged that it will make contact with another contact-point on the frame of the press and close one break in a similar circuit through the releasing-magnets in order to cut off the power and to deenergize clutch 31 and to do this automatically. In this same circuit I place a switch which can be opened or closed by hand as desired. If it is desired to have an automatic stoppage of the hoisting-arms when they reach their highest point, the switch is closed. Otherwise it is left open. This switch is shown at 108 in Fig. 1 and is there shown in its open position. If it is desired to have 105 such automatic stoppage, switch 108 is closed. My device to cause this automatic stoppage is as follows: 103 is an arm connected to one of the hoisting-arms and carrying a contact-point 104, which is adapted to make contact 110 when the hoisting-arm is in highest position with contact-point 105 on the framework of the carriage. Contact-point 104 is electrically connected with wire 106, which connects with wire 44. When contact-points 104 and 105 115 are in contact with each other, the following circuit is closed through the releasing-magnets 62, 69, and 67—namely, switch 37, wire 38, strip 40, wire 44, wire 106, contact-points 104 105, wire 107, switch 108, (when closed,) wire 109, wire 102, wire 65, magnet 62, wire 66, magnet 67, wire 68, magnet 69, wire 70, part of wire 51, contact-points and bridge of circuit-controller 48, wire 55, wire 42, strip 41, wire 39, to the other side of switch 37. 120 By closing switch 108, therefore, the automatic stoppage of the hoisting-arms in their upward movement is assured.

In the preferred form of my invention a common circuit through releasing-magnets 125 62, 67, and 69 is used, although, if desired, separate rail-circuits through each magnet might be used. One advantage of having a common circuit is that upon pressing any one

of the push-buttons 61, 81, or 95 all of the releasing-magnets are energized and the power is shut off from the motor, and both the clutches are deenergized, thus making the 5 stoppage at the particular part desired the more certain. In this way also the automatic stoppage of the carriage at any desired point upon the rails and the automatic devices for stopping the upward movement of the hoisting-arms also affect all three releasing-magnets and shut off the power and deenergize both clutches.

In Fig. 1 only the wires 50 and 51 running to the armature are shown, the wires running 15 to the fields of motor 11 being omitted from that view.

In Fig. 6 I have shown the wires running to the fields of the motor and their connection with the rest of the system. 110 is a wire 20 running from one side of the fields of the motor connecting with main-line wire 44. 111 is a wire running from the other side of the fields of the motor connecting with an additional set of contact-points and bridge of circuit-controller 48—to wit, the top set of contact-points and bridge of that circuit-controller, wire 112 running from the contact-points and connecting with the other main-line wire 42. Thus every time the circuit-controller 48 is closed or opened the circuit 25 through the fields will be closed or opened irrespective of reversing-switch 43. By reversing the currents through the armature the motor may accordingly be driven in one 30 direction or the other, as desired.

In the construction shown in Fig. 1 the devices for automatically stopping the carriage at any given point or for stopping the hoisting-arms when they reach their highest position are operated only when the reversing-switch is in one position and are not operated when the switch is in the other position. Automatic switches for stopping the carriage or the hoisting-arms when the switch is in the 40 latter position can be inserted, if desired, by merely connecting the switches with the opposite rail from that with which switches 97 and 97^a (shown in Fig. 1) are connected. I prefer, however, to arrange the circuit so that 45 but one set of switches need be employed, and I show this system in Fig. 6 as far as is necessary to make the same intelligible. This I accomplish by omitting wire 70, running from magnet 69, and by running a wire 113 from that magnet directly to main-line wire 42, thus completing the circuit without passing through switch 43. The reversal of the switch therefore has no effect upon the operation of the automatic devices. For the same 50 reason I preferably connect wire 84 directly with main-line wire 44 by wire 114 instead of by wires 59 and 45, thus closing the circuits through push-buttons 61, 81, and 95 without having the circuit pass through reversing-switch 43. In all other respects the 55 circuits shown in Fig. 6 are like those shown in Fig. 1.

What I claim as new, and desire to secure by Letters Patent, is—

1. In a press, the combination of a movable carriage, rails along which the carriage is adapted to move, an electric motor thereon for driving the carriage, a circuit through the motor, normally broken, a circuit-controller therein, normally open, an operating-circuit, 70 an electromagnet therein for controlling the circuit-controller of the first circuit, and means for making and breaking the operating-circuit at will, whereby the carriage may be moved along the rails at will.

2. In a press, the combination of a movable carriage, rails along which the carriage is adapted to move, an electric motor thereon for driving the carriage, a circuit through the motor, normally broken, a circuit-controller 80 therein, normally open, an operating-circuit, an electromagnet therein for closing the circuit-controller of the first circuit, means for making or breaking the operating-circuit at will, a catch for holding said circuit-controller 85 in its closed position, a releasing-circuit, an electromagnet therein adapted to withdraw the catch from its operative position when the releasing-magnet is energized, and means for making and breaking the releasing-circuit at will whereby the carriage may be moved 90 along the rails and may be stopped at will.

3. In a press, the combination of a movable carriage, rails along which the carriage is adapted to move, an electric motor thereon 100 for driving the carriage, a circuit through the motor, normally broken, containing a reversing-switch, a circuit-controller therein, normally open, an operating-circuit, an electromagnet therein for controlling the circuit-controller of the first circuit, and means for making and breaking the operating-circuit at will, whereby the carriage may be moved 105 along the rails at will.

4. In a press, the combination of a movable carriage, rails along which the carriage is adapted to move, an electric motor thereon for driving the carriage, a circuit through the motor, normally broken, containing a reversing-switch, a circuit-controller therein, normally open, an operating-circuit, an electromagnet therein for closing the circuit-controller of the first circuit, means for making or breaking the operating-circuit at will, a catch for holding said circuit-controller in its 115 closed position, a releasing-circuit, an electromagnet therein adapted to withdraw the catch from its operative position when the releasing-magnet is energized, and means for making and breaking the releasing-circuit at will 120 whereby the carriage may be moved along the rails and may be stopped at will.

5. In a press, the combination of a movable carriage, hoisting-arms connected therewith and means for operating said arms, rails along 130 which the carriage is adapted to move, an electric motor thereon for driving the carriage, a circuit through the motor, normally broken, a circuit-controller therein, normally

open, an operating-circuit, an electromagnet therein for controlling the circuit-controller of the first circuit, and means for making and breaking the operating-circuit at will, where-
5 by the carriage may be moved along the rails at will.

6. In a press, the combination of a movable carriage, hoisting-arms connected therewith and means for operating said arms, rails along
10 which the carriage is adapted to move, an electric motor thereon for driving the carriage, a circuit through the motor, normally broken, a circuit-controller therein, normally open, an operating-circuit, an electromagnet
15 therein for closing the circuit-controller of the first circuit, means for making and breaking the operating-circuit at will, a catch for holding said circuit-controller in its closed position, a releasing-circuit, an electromagnet
20 therein adapted to withdraw the catch from its operative position when the releasing-magnet is energized, and means for making and breaking the releasing-circuit at will, whereby the carriage may be moved along the rails
25 and may be stopped at will.

7. In a press, the combination of a movable carriage, hoisting-arms connected therewith and means for operating the said arms, rails along which the carriage is adapted to move,
30 a motor for driving the carriage, connecting mechanism between the motor and the wheels of the carriage for imparting motion to the carriage, an electric clutch forming part of said connecting mechanism and adapted to
35 cause the connecting mechanism to connect the motor operatively with the wheels to drive them or to disconnect them, a circuit through the electric clutch, a circuit-controller therein, under the control of the operator, for making
40 and breaking the circuit through the clutch, whereby the carriage may be moved along the rails at will.

8. In a press, the combination of a movable carriage, hoisting-arms connected therewith
45 and means for operating the said arms, rails along which the carriage is adapted to move, a motor for driving the carriage, connecting mechanism between the motor and the wheels of the carriage for imparting motion to the
50 carriage, an electric clutch forming part of said connecting mechanism and adapted to cause the connecting mechanism to connect the motor operatively with the wheels to drive them or to disconnect them, a circuit through
55 the electric clutch, a circuit-controller therein, an operating-circuit, an electromagnet therein for controlling the circuit-controller of the first circuit, and means for making and breaking the operating-circuit at will, whereby the carriage
60 may be moved along the rails at will.

9. In a press, the combination of a movable carriage, hoisting-arms connected therewith and means for operating the said arms, rails along which the carriage is adapted to move,
65 a motor for driving the carriage, connecting mechanism between the motor and the wheels of the carriage for imparting motion to the

carriage, an electric clutch forming part of said connecting mechanism and adapted to cause the connecting mechanism to connect
70 the motor operatively with the wheels to drive them or to disconnect them, a circuit through the electric clutch, a circuit-controller therein, an operating-circuit, an electromagnet therein for closing the circuit-controller of the first
75 circuit, means for making and breaking the operating-circuit at will, a catch for holding said circuit-controller in its closed position, a releasing-circuit, an electromagnet therein adapted when energized to withdraw the catch
80 to permit the circuit-controller of the first circuit to open to break said circuit, whereby the carriage may be moved along the rails and may be stopped at will.

10. In a press, the combination of a movable carriage, rails along which the carriage is adapted to move, a motor, hoisting-arms connected with the carriage, connecting mechanism between the motor and the hoisting-arms for imparting motion from the motor to the
90 hoisting-arms to raise or lower them, an electric clutch forming part of said connecting mechanism and adapted to cause the connecting mechanism to connect the motor operatively with the hoisting-arms to raise them
95 or lower them or disconnect them, a circuit through the electric clutch, a circuit-controller therein, under the control of the operator, for making and breaking the circuit through the clutch, whereby the hoisting-arms may
100 be raised or lowered at will.

11. In a press, the combination of a movable carriage, rails along which the carriage is adapted to move, a motor, hoisting-arms connected with the carriage, connecting mechanism between the motor and the hoisting-arms for imparting motion from the motor to the hoisting-arms to raise or lower them, an electric clutch forming part of said connecting mechanism and adapted to cause the connecting mechanism to connect the motor operatively with the hoisting-arms to raise them
110 or to lower them or disconnect them, a circuit through the electric clutch, a circuit-controller therein, an operating-circuit, an electromagnet therein for controlling a circuit-controller of the first circuit, and means for making and breaking the operating-circuit at will, whereby the hoisting-arms may be raised
115 or lowered at will.

12. In a press, the combination of a movable carriage, rails along which the carriage is adapted to move, a motor, hoisting-arms connected with the carriage, connecting mechanism between the motor and the hoisting-arms for imparting motion from the motor to the hoisting-arms to raise or lower them, an electric clutch forming part of said connecting mechanism and adapted to cause the connecting mechanism to connect the motor operatively with the hoisting-arms to raise them
125 or to lower them or disconnect them, a circuit through the electric clutch, a circuit-controller therein, an operating-circuit, an elec-

tromagnet therein for controlling the circuit-controller of the first circuit, and means for making and breaking the operating-circuit at will, a catch for holding said circuit-controller

5 in its closed position, a releasing-circuit, an electromagnet therein adapted, when energized, to withdraw the catch to permit the circuit-controller of the first circuit to open to break said circuit, and means for making and 10 breaking the releasing-circuit, whereby the hoisting-arms may be raised or lowered at will.

13. In a press, the combination of a movable carriage, rails along which the carriage 15 is adapted to move, an electric motor connected with the carriage, connecting mechanism between the motor and the wheels of the carriage for imparting motion to the carriage, an electric clutch forming part of said connecting mechanism and adapted to cause the connecting mechanism to connect the motor operatively with the wheels to drive them or to disconnect them, hoisting-arms connected with the carriage, connecting mechanism between the motor and the hoisting-arms for imparting motion to the latter to raise or lower them, an electric clutch forming part of said connecting mechanism and adapted to cause the connecting mechanism to connect the motor operatively with the hoisting-arms to raise or lower them or to disconnect them, a circuit through the electric motor and a circuit through each of the 30 electric clutches, a circuit-controller in each of said circuits, under the control of the operator, an operating-circuit for each of said circuits, an electromagnet in each operating-circuit for controlling the circuit-controller of the corresponding first circuit, and means for making and breaking each of the operating-circuits at will, a catch for holding each 35 of said circuit-controllers in its closed position, a releasing-circuit for each catch, an electromagnet in each releasing-circuit adapted when energized to withdraw its catch to permit the circuit-controller of the corresponding first circuit to break said circuit, whereby the carriage may be moved along the rails and the hoisting-arms may be raised or lowered at will.

14. In a press, the combination of a movable carriage, rails along which the carriage is adapted to move, an electric motor connected with the carriage, connecting mechanism between the motor and the wheels of the carriage for imparting motion to the carriage, an electric clutch forming part of said connecting mechanism and adapted to cause the connecting mechanism to connect the motor operatively with the wheels to drive them or to disconnect them, hoisting-arms connected with the carriage, connecting mechanism between the motor and the hoisting-arms for imparting motion to the latter to raise or lower them, an electric clutch forming part of said connecting mechanism and adapted to cause the connecting mechanism to connect the motor operatively with the hoisting-arms to raise or lower them or to disconnect them, a circuit through the electric motor and a circuit through each of the electric clutches, a circuit-controller in each of said circuits, under the control of the operator, an operating-circuit for each of said circuits, an electromagnet in each operating-circuit for controlling the circuit-controller of the corresponding first circuit, and means for making and breaking each of the

operating-circuits at will, whereby the carriage may be moved along the rails and the hoisting-arms may be raised or lowered at will.

15. In a press, the combination of a movable carriage, rails along which the carriage is adapted to move, an electric motor connected with the carriage, connecting mechanism between the motor and the wheels of the carriage for imparting motion to the carriage, an electric clutch forming part of said connecting mechanism and adapted to cause the connecting mechanism to connect the motor operatively with the wheels to drive them or to disconnect them, hoisting-arms connected with the carriage, connecting mechanism between the motor and the hoisting-arms for imparting motion to the latter to raise or lower them, an electric clutch forming part of said connecting mechanism and adapted to cause the connecting mechanism to connect the motor operatively with the hoisting-arms to raise or lower them or to disconnect them, a circuit through the electric motor and a circuit through each of the electric clutches, a circuit-controller in each of said circuits, under the control of the operator, an operating-circuit for each of said circuits, an electromagnet in each operating-circuit for controlling the circuit-controller of the corresponding first circuit, and means for making and breaking each of the operating-circuits at will, a catch for holding each of said circuit-controllers in its closed position, a releasing-circuit for each catch, an electromagnet in each releasing-circuit adapted when energized to withdraw its catch to permit the circuit-controller of the corresponding first circuit to break said circuit, whereby the carriage may be moved along the rails and the hoisting-arms may be raised or lowered at will.

16. In a press, the combination of a movable carriage, rails along which the carriage is adapted to move, an electric motor connected with the carriage, connecting mechanism between the motor and the wheels of the carriage for imparting motion to the carriage, an electric clutch forming part of said connecting mechanism and adapted to cause the connecting mechanism to connect the motor operatively with the wheels to drive them or to disconnect them, hoisting-arms connected with the carriage, connecting mechanism between the motor and the hoisting-arms for imparting motion to the latter to raise or lower them, an electric clutch forming part of said connecting mechanism and adapted to cause the connecting mechanism to connect the motor operatively with the hoisting-arms to raise or lower them or to disconnect them, a circuit through the electric motor and a circuit through each of the electric clutches, a circuit-controller in each of said circuits, under the control of the operator, an operating-circuit for each of said circuits, an electromagnet in each operating-circuit for controlling the circuit-controller of the corresponding first circuit, and means for making and breaking each of the

- ling the circuit-controller of the corresponding first circuit, and means for making and breaking each of the operating-circuits at will, a catch for holding each of said circuit-controllers in its closed position, an electromagnet for each catch adapted when energized to withdraw its catch to permit the circuit-controller of said first circuit to open to break said circuit, a circuit common to all of said 5 releasing-magnets, and means for making and breaking said circuit, whereby the carriage may be moved along the rails and the hoisting-arms may be raised or lowered at will.
- 15 17. In a press, the combination of a movable carriage, hoisting-arms connected therewith and means for operating said arms, rails along which the carriage is adapted to move, a motor for driving the carriage, connecting 20 mechanism between the motor and the wheels of the carriage for imparting motion to the carriage, an electric clutch forming part of said connecting mechanism and adapted to cause the said connecting mechanism to connect the motor operatively with the wheels to drive them or to disconnect them, a circuit through the electric clutch, a circuit-controller therein, an operating-circuit, an electromagnet therein for closing the circuit-controller 25 of the first circuit, means for making and breaking the operating-circuit at will, a catch for holding said circuit-controller in its closed position, an electromagnet adapted when energized to withdraw the catch to permit 30 the circuit and controller of the first circuit to open to break said circuit, a releasing-circuit through said electromagnet, a contact-point secured on the carriage and forming part of said releasing-circuit, one or more 35 contact-points also in said circuit arranged along the rails at any desired point or points, all so arranged that when the contact-point on the carriage makes contact with any said contact-points on the rails, the releasing-circuit will be closed through said releasing-magnet, whereby the carriage may be automatically stopped at a predetermined point.
- 40 18. In a press, the combination of a movable carriage, hoisting-arms connected therewith and means for operating said arms, rails along which the carriage is adapted to move, a motor for driving the carriage, connecting 45 mechanism between the motor and the wheels of the carriage for imparting motion to the carriage, an electric clutch forming part of said connecting mechanism and adapted to cause the said connecting mechanism to connect the motor operatively with the wheels to drive them or to disconnect them, a circuit through the electric clutch, a circuit-controller therein, an operating-circuit, an electromagnet therein for closing the circuit-controller of the first circuit, means for making and breaking the operating-circuit at will, a catch for holding said circuit-controller in its closed position, an electromagnet adapted when energized to withdraw the catch to permit 50 the circuit and controller of the first circuit to open to break said circuit, a releasing-circuit through said electromagnet, a contact-point secured on the carriage and forming part of said releasing-circuit, one or more contact-points also in said circuit arranged along the rails at any desired point or points, all so arranged that when the contact-point on the carriage makes contact with any said contact-points on the rails, the releasing-circuit will be closed through said releasing-magnet, whereby the carriage may be automatically stopped at a predetermined point.
- 55 19. In a press, the combination of a movable carriage, rails along which the carriage is adapted to move, a motor, hoisting-arms connected with the carriage, connecting mechanism between the motor and the hoisting-arms for imparting motion from the motor to the hoisting-arms to raise or lower them, an electric clutch forming part of said connecting mechanism and adapted to cause the connecting mechanism to connect the motor operatively with the hoisting-arms to raise them or to lower them or disconnect them, a circuit through the electric clutch, a circuit-controller therein, an operating-circuit, an electromagnet therein for controlling the circuit-controller of the first circuit, and means for making and breaking the operating-circuit at 60 will, a catch for holding said circuit-controller in its closed position, a releasing-circuit, an electromagnet therein adapted, when energized, to withdraw the catch to permit the circuit-controller of the first circuit to open to break said circuit, a set of contact-points in said releasing-circuit, one of said contact-points being carried by one of the hoisting-arms and the other borne upon the framework of the carriage and so arranged that when the hoisting-arms are in their raised position the two contact-points will make contact with each other to close the said releasing-circuit, whereby the upward movement of the hoisting-arms will be automatically stopped at the proper point.
- 65 20. In a press, the combination of a movable carriage, rails along which the carriage is adapted to move, a motor, hoisting-arms connected with the carriage, connecting mechanism between the motor and the hoisting-arms for imparting motion from the motor to the hoisting-arms to raise or lower them, an electric clutch forming part of said connecting mechanism and adapted to cause the connecting mechanism to connect the motor operatively with the hoisting-arms to raise them or to lower them or disconnect them, a circuit through the electric clutch, a circuit-controller therein, an operating-circuit, an electromagnet therein for controlling the circuit-controller of the first circuit, and means for making and breaking the operating-circuit at will, a catch for holding said circuit-controller in its closed position, an electromagnet adapted when energized to withdraw the catch to permit the circuit and controller of the first circuit to open to break said circuit, a releasing-circuit through said electromagnet, a contact-point secured on the carriage and forming part of said releasing-circuit, one or more contact-points also in said circuit arranged along the rails at any desired point or points, a switch for each of said contact-points along the rails adapted to be opened or closed at will, all so arranged that when one of said switches is closed and when the contact-point on the carriage makes contact with the corresponding contact-point on the rails, the releasing-circuit through the releasing-magnet will be closed, whereby the carriage may be automatically stopped at a predetermined point.
- 70 75 80 85 90 95 100 105 110 115 120 125 130

in its closed position, a releasing-circuit, an electromagnet therein, adapted, when energized, to withdraw the catch to permit the circuit-controller of the first circuit to open to 5 break said circuit, a set of contact-points in said releasing-circuit, one of said contact-points being carried by one of the hoisting-arms and the other borne upon the framework of the carriage and so arranged that when the 10 hoisting-arms are in their raised position the two contact-points will make contact with each other, a switch in said releasing-circuit adapted to be opened or closed at will, whereby when said switch is closed and the said con-

tact-points make contact with each other 15 through the upward movement of the hoisting-arms, the releasing-circuit will be closed, the catch withdrawn and the circuit through the electric clutch be broken and the upward movement of the hoisting-arms be automatically stopped. 20

In testimony whereof I have signed my name to this specification in the presence of two subscribing witnesses.

EDWARD HETT.
